Primary Examiner — Jonathan J Han*Assistant Examiner* — Molly K. Orzechowski(74) *Attorney, Agent, or Firm* — Casimir Jones, S.C.; Brian F. Bradley(57) **CLAIM**

The ornamental design for a sandal, as shown and described.

DESCRIPTION

FIG. 1 is a perspective view showing the new design of a sandal;
 FIG. 2 is another perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines depict portions of the sandal which form no part of the claimed design.

1 Claim, 8 Drawing Sheets(56)
